UNITED STATES PATENT OFFICE.

ROBERT LAGUS, OF ABO, FINLAND.

TREE-FELLING MACHINE.

1,302,932.

Specification of Letters Patent.

Patented May 6, 1919.

Application filed April 18, 1918. Serial No. 91,853.

To all whom it may concern:

Be it known that I, ROBERT LAGUS, a subject of the Grand Duke of Finland, and resident of 14 Lilla Tavastgatan, Åbo, in the Grand Duchy of Finland, have invented certain new and useful Improvements in Tree-Felling Machines, of which the following is a specification, reference being had therein to the accompanying drawing.

10 This invention relates to a portable tree felling machine. The said machine consists of a horizontal ring, disk or the like mounted in a rotatable manner on a barrow or any other suitable support, which ring, etc., carries a suitable motor and a sliding rod, which is reciprocated by the motor by means of a suitable motion transmitting device and carries the saw-blade. The said machine also has a rod, guiding the saw-blade, while it 20 cuts itself into the tree, and a device, by means of which the barrow is firmly connected with the tree to be felled.

My invention consists of the construction, combination and arrangement of parts, as 25 herein illustrated, described and claimed.

In the accompanying drawings, forming part hereof, I have illustrated a form of embodiment of my invention, in which drawings similar reference characters designate 30 corresponding parts, and in which:

Figure 1 is a side elevation;

Fig. 2 is a plan view; and

Fig. 3 is a fragmentary detail in cross section.

35 The said machine comprises a barrow, consisting of side bars 1 connected by cross bars 2. In one of the said cross bars 2 a pin 3 is fixed, around which can rotate a horizontal ring 4 (disk or the like) provided 40 with a diametrical bar 5, in which there is an opening for the pin 3. The said ring is provided with a handle 6, by means of which the ring 4 can be rotated manually around the pin 3. A suitable motor 7, in the drawing shown as an internal combustion engine, is carried by the ring 4. In guides 8, fixed to the ring 4, a rod 9 is slidably mounted, and carries at its forward end a saw-blade 10. To the shaft 11 of the motor 7 a toothed 45 wheel 12 is fixed to mesh with a toothed wheel 13 rotatably mounted on a pin 14, which is fixed to a bar 15, connected with the ring 4. On the said bar 15 a bearing 16 for the motor shaft 11 is provided. The 50 toothed wheel 13 has a crank pin 17 and a pitman 18 is connected with the said pin and

a pin 19, fixed to the bar 9. Owing to the said arrangement a reciprocating movement is imparted to the bar 9 and the saw-blade 10 by the motor, while operating. A pin 20 is fixed to the ring 4 about which can rock a bar 21, the fore end of which forms a groove shaped guide adapted to engage the back of the saw-blade 10, Fig. 3. The rear end of the said bar 21 is acted upon by a 60 spring 22, fixed to the ring 4, so that the forward end of the bar 21 is forced against the back of the saw-blade and guides the same, while it cuts itself into the tree, as 65 described below.

A cable 23 is connected with a hook 24 provided in the forward end of the barrow, at one side of the same. The said cable is placed around the tree to be cut and passes through a ring 25 fixed to the fore end of 70 the barrow at the opposite side of the same with relation to the hook 24. The end of the cable 23 is secured to a hand lever 26, pivoted to an upright 27, which is provided on the barrow. The cable is tightened around 75 the tree by means of the hand lever, which is held in operative position by any suitable means for instance by teeth 28 provided on the barrow, which are engaged by the lower end of the hand lever 26. In order to engage or disengage the hand lever 26 with or from the teeth 28 there is a slight play between the lever and its pivot 26*. The engagement of the lever with the teeth is maintained by the tension of the cable acting to 80 toward the barrow. To the curve shaped front cross bar 2 of the barrow teeth 29 are secured, which are forced into the tree, as the cable 23 is tightened around the same. The handles 30 are pivoted to the barrow in such 85 manner, that they can be swung outward into the position shown by dotted lines. By means of the handles the operators can move the machine from tree to tree. While the machine is in operation, the said handles 90 occupy the position shown by full lines.

When a tree is to be cut off the barrow is fixed to the same by means of the cable 23 and in the manner stated above, immediately 95 above the ground. The barrow is then brought into a horizontal position by means of adjusting screws 31, provided in the rear end of the same. After the motor 7 has been started, the saw-blade is forced against the tree by rotating the ring 4 by means of the 100 handle 6. By feeding the saw through the tree normally, the operator can always 105 con-

trol the work of the saw, so that there will be no risk of the feed becoming too rapid, which would cause the saw-blade to break or stop the motor. While the saw-blade cuts 5 itself into the tree, the rod 21 guides the same, until the rod contacts with the tree. The rod is then stopped in its motion, while the saw-blade passes farther into the tree.

Having now described my invention, what 10 I claim as new and desire to secure by Letters Patent is,

In a tree-felling machine, the combination comprising a support, a rotatable horizontally disposed member on the support, a mo-

tor on the rotatable member, a rod slidably 15 disposed on the rotatable member and arranged to be moved by the motor, a saw-blade connected to the rod, a U-shaped rod pivoted to the rotatable member and arranged to engage the back of the saw on the 20 commencement of a cut, and a spring member having one end secured to the rotatable member and its opposite end secured to the rear end of the U-shaped member.

In witness whereof, I have hereunto 25 signed my name.

ROBERT LAGUS.
